UNITED STATES PATENT OFFICE.

WILLIAM H. NEWTON, OF ASSUMPTION, ILLINOIS.

TABLE.

SPECIFICATION forming part of Letters Patent No. 340,921, dated April 27, 1886.

Application filed May 20, 1884. Renewed March 2, 1886. Serial No. 193,806. (No model.)

To all whom it may concern:

Be it known that I, WILLIAM H. NEWTON, a citizen of the United States of America, residing at Assumption, in the county of Chrys-tain and State of Illinois, have invented cer-tain new and useful Improvements in Tables, of which the following is a specification, ref-erence being had therein to the accompanying drawings.

10 This invention pertains to improvements in table-waiters, having for its object to enable persons seated at a table to conveniently sup-ply themselves, and without assistance, while the center of the table may be decorated with a bouquet of flowers; and the invention consists 15 of the combination of parts and their construc-tion, substantially as hereinafter fully set forth, and pointed out in the claim.

In the accompanying drawings, Figure 1 is a 20 sectional elevation of my invention. Fig. 2 is a side elevation, and Fig. 3 is a plan view, of the same.

In carrying out my invention I employ a ta-ble, A, which may have a square top surface 25 and be beveled off from a short distance below its vertical sides toward its lower end. The leaves A', of which there are preferably four, are correspondingly recessed, to enable them to rest upon the ledges thus formed upon the 30 sides of the table-top, said leaves being sup-ported by the horizontal portion of angle-irons a, the vertical arms of which enter or pass into sockets a', fastened to the sides of the frame of the table by set-screws passing through ex-tension-plates of the sockets a', and to permit 35 said leaves to be readily extended or lowered.

B B' B² are disks or shelves of varying di-ameters, tapering in size toward the top, the 40 lower one or largest resting contiguously to the table-top upon a block, b, so as to revolve, and near its outer edge upon anti-frictional rolls or wheels b', supported in the usual way in boxes let into sockets in the table-top, which shelf may serve to hold the edibles. The in-45 termediate shelf, or next in size, is fastened to

and supported upon a tube or hollow shaft, d, extending down through an inclosing case or post, d', resting upon the shelf B, and through the latter and its central block-support, b, to and resting upon the table-top, which shelf 50 may serve to hold viands or confectionaries. The uppermost shelf, or smallest, is secured to and mounted upon a similar tube or hollow shaft, e, and is disposed within the tube or shaft d and stands upon the table-top, said 55 tube or shaft e having previously been passed through an inclosing case or post, e', resting upon the shelf B', and through the latter shelf, which shelf B' may serve as a bouquet-holder or flower-stand. The entire superposed struc-ture thus made is connected to the table-top and rendered stable by a rod, f, secured to the 60 topmost shelf and extending through the innermost tube or shaft, e, and the table-top, being bolted to the under side of the table-top 65 frame. This disposition of parts, it is obvi-ous, permits persons seated at the table to con-veniently wait upon themselves, and without the assistance of a servant, the rotation of the shelf having the desired article being readily 70 effected simply by applying the hand thereto with almost unappreciable force to bring the article or articles opposite the plate, said shelves being sensitively mounted in the man-ner above described.

Having thus fully described my invention, what I claim, and desire to secure by Letters Patent, is—

The anti-frictional rolls b', secured to the table-top, in combination with the shafts d and 80 e, supporting, respectively, the revolving shelves B' and B², and the nutted rod f, sub-stantially as shown and described.

In testimony whereof I affix my signature in presence of two witnesses.

WILLIAM H. NEWTON.
